UNITED STATES PATENT OFFICE.

STEPHEN F. BRIGGS, OF MILWAUKEE, WISCONSIN, ASSIGNOR TO BRIGGS & STRATTON COMPANY, OF MILWAUKEE, WISCONSIN, A CORPORATION OF WISCONSIN.

KEY-CONTROLLED LIGHTING AND IGNITION SWITCH.

Application filed March 15, 1915. Serial No. 14,418.

To all whom it may concern:

Be it known that I, STEPHEN F. BRIGGS, a citizen of the United States, and resident of Milwaukee, and county of Milwaukee, and 5 State of Wisconsin, have invented new and useful Improvements in Key-Controlled Lighting and Ignition Switches, of which the following is a description, reference being had to the accompanying drawings, 10 which are a part of this specification.

This invention has for its object to provide a switch depending upon the presence of a removable key for its operation, and adapted to control the lighting and ignition 15 circuits of an automobile or the like.

Another object of the invention is to provide such a key controlled switch with a spring contact member for controlling the ignition circuit, and adapted when the key 20 is removed, to spring to a position for rendering the ignition circuit ineffective as well as for engaging stops for preventing the 25 operation of the switch.

Another object of the invention is to perfect details of construction of switch mechanism of this character.

With the above and other objects in view the invention consists in the key controlled lighting and ignition switch as herein 30 claimed and all equivalents.

Referring to the accompanying drawings, in which like characters of reference indicate the same parts in the different views,

Fig. 1 is a front view of a switch constructed in accordance with this invention;

Fig. 2 is a rear view thereof;

Fig. 3 is a sectional plan view showing by dotted lines the position of the switch in the "off" position;

Fig. 4 is a similar view showing the switch in the "dim" position in which the small headlights and the taillights are burning;

Fig. 5 is a similar view showing the switch in the "on" position in which the large head- 45 lights and the taillights are burning;

Fig. 6 is a rear view with the base or terminal head removed;

Fig. 7 is a central sectional view of the switch with the key removed;

Fig. 8 is a similar view with the key in place;

Fig. 9 is a sectional elevation showing the ignition spring contact fitting between stop

lugs on the switch member for locking the switch; and,

Fig. 10 is a rear view of the hub with the switch member or contact disk removed.

Fig. 11 is a detail view of the key guide.

In these drawings 10 indicates a casing or cylindrical sheet metal shell with one end turned inwardly to form a flange. Fitting in the other end of the casing is a flanged base or terminal head 11 of insulating material to which the shell or hood is removably attached by means of screws. The base or terminal head 11 has a recess in its upper face and has arranged around said recess a circular series of depressions 12, some of which are formed in metal contact bushings which are forced into openings in the base, and on the bottom of the base form binding posts 13, 14, 15 and 16 respectively. Within the recess of the base there is mounted a contact spring 17 by having a broadened end bent under and secured to the base by screws 18, one of which fits in a bushing 19 which is connected by a metal strip 20 on the bottom of the base with the binding post 13. The other end of the spring extends outwardly and then downwardly with its end positioned above a contact bushing which forms a binding post 21, the bent portion of the spring being confined within an arched staple 22 which is secured to and projects above the base. A switch member or contact disk 23 of insulating material is carried by the base part of the switch by having a hub 24 secured thereto and fitting within the opening between the edges of the inturned flange of the casing, and secured to the bottom of this disk 23 is a sheet metal spider 25 having radial arms with their ends convexed to fit the depressions 12 in the base, said spider being preferably in duplicate to increase the durability thereof. The spring action of these radial contact arms of the spider bearing upon the top of the base 11 serves to hold the disk 23 in its bearing relation against the flange of the casing, and suitable spacing posts 26 project from the disk 23 and engage the base 11 to limit the movement of the disk 23 toward the base. A pair of stop pins 27 project from the edge of the disk 23 and are adapted to engage a stop lug 28 pressed in from the side of the casing 10 to limit the turning movements of the switch.

member. A handle 29 is countersunk in and secured to the hub 24 and has a central cylindrical opening extending from its lower end to near its upper end where it is provided with a keyhole slot 30 through which a key 31 may pass and occupy the slot which extends entirely through the cylindrical upper portion of a key guide 32 fitting within said cylindrical opening of the handle. The key 32, besides its split cylindrical upper portion, has a boss 33 at its lower end which forms a central connection for the lower ends of the two sections of the split cylindrical portion, and parallel fingers 34 projecting from the end of the key 31 embrace the opposite sides of boss 33 and engage the flanged upper end of a thimble or tubular plunger 35 which fits on the boss 33 and has a plug 36 of insulating material at its lower end by which it engages the contact spring 17. The plunger 35 is pressed upwardly by the contact spring 17 and is held thereby against the bottom of the cylindrical upper portion of the key guide 32 when the key is removed, but is forced downwardly by the fingers 34 of the key when the key is inserted, thus depressing the contact spring 17 until it engages the terminal contact 21. The key on being inserted through the keyhole 30 and pressed inwardly to effect this connection is held in place by giving it a quarter turn which is permitted by the notches in the opposite edges thereof receiving the flanged portion of the handle in which the keyhole is formed, and the upward spring pressure against the key holds it seated against suitable notches on the bottom surface of the said flanges.

A pair of locking pins 37 project from the bottom surface of the disk 23 in position to receive the contact spring 17 between them when the key is withdrawn from the switch in the intermediate or "off" position, as best seen in Figs. 3 and 9, but when the key is inserted and the spring 17 is depressed it is carried out of the path of travel of said locking pins, as best seen in Fig. 8, so that the switch may freely turn. If the key is removed in either of the other positions of the switch the spring 17 will prevent turning in one direction, and the engagement of the stop pin 27 with the stop lug 28 will prevent turning of the switch in the other direction.

In connecting up the switch of this invention the binding posts 19 and 21 are connected with the terminals of a gas engine ignition circuit, and the binding posts formed by the contact bushings 13, 14, 15 and 16 are connected with the battery, taillight, small headlight, and the large headlight respectively. When the switch is in the "off" position, shown in Fig. 3, there is no spring arm of the spider 25 in engagement with the battery contact 13, and consequently none of the lamps are burning, but in the

"dim" position of the switch, shown in Fig. 4, the spring arms of spider 25 are in engagement with battery contact 13, taillight contact 14, and small headlight contact 15, so that the taillights and the small headlights are burning, while in the "on" position of the switch, shown in Fig. 5, the battery contact 13, the taillight contact 14, and the large headlight contact 16 are engaged by the spring arms of the spider 25 so that the taillights and the large headlights are burning. The small headlight controlled by contact 15 may consist of separate lamp bulbs from those used for the large headlights, or they may be the same lamp bulbs with dimming resistance in series therewith. It will thus be seen that by changing the switch from the "on" position to the "dim" position the taillights are unaffected but the headlights are dimmed. This dimming effect may be produced by the use of large and small headlight lamps in separate circuits or by the use of single headlight lamps with dimming resistance in series therewith to be included or excluded by the switch in the manner shown in my co-pending application Serial No. 12,873 for lighting and ignition switch, filed March 8, 1915.

In operation the switch mechanism of this invention combines in the contact spring a switch member for controlling the ignition of the gas engine and a means for locking the lighting switch against operation, both depending upon the presence of the key which therefore constitutes a removable handle for the ignition switch and serves to disable the locking means for the lighting switch by its attachment. When the key is removed from the switch in any position thereof the switch can not be turned to change the lighting connections, and the engine can not be operated, for its ignition circuit is opened by the contact spring 17 moving out of engagement with the terminal contact 21. As soon as the key is returned, however, the ignition circuit is restored, and the contact spring 17 being depressed by the plunger 35 out of the path of travel of the locking lugs 37, the switch may be freely turned to any position desired.

The arrangement of the contact bushings and the spring arms of the spider 25 may be varied to suit the requirements as the switch is not confined to the particular connections shown.

It is obvious that the ignition control may be effected by the spring 17 closing a circuit by engaging a contact on the removal of the key, as required with magneto ignition.

What I claim as new and desire to secure by Letters Patent is:

1. An ignition and lighting switch, comprising a spring actuated member for controlling an ignition circuit, a movable switch member for controlling a lighting circuit

- engaged and locked by the spring actuated member, and a key for moving the spring actuated member out of locking engagement with the switch member to a position for rendering the ignition circuit effective.
2. A combined lighting and ignition switch having a contact spring for controlling an ignition circuit, a switch member for controlling a lighting circuit engaged and locked by the contact spring, and a key for forcing the contact spring out of locking engagement with the switch member and into a position for rendering the ignition circuit effective.
3. A combined lighting and ignition switch, comprising a contact spring, a contact adapted to be engaged thereby for controlling an ignition circuit, a rotatable switch member for controlling a lighting circuit and having means for engaging the contact spring to be locked thereby against turning, a plunger slidably mounted in the switch member and engaging the contact spring, and a key removably fitting in the switch member and adapted to engage and depress the plunger to move the contact spring out of locking engagement with the switch member and into engagement with the contact.
4. A combined ignition and lighting switch, comprising an insulating base, a contact thereon, a contact spring mounted on the insulating base and capable of being moved into engagement with the contact to control an ignition circuit, a casing mounted on the base, a rotary switch member mounted in the casing, means on the switch member to be engaged by the contact spring for locking the switch member against turning, contact arms carried by the switch member, contacts on the base engaged by the contact arms for controlling a lighting circuit, a plunger slidably mounted in the switch member, and a key removably fitting in the switch member and adapted to depress the plunger to force the contact spring out of locking engagement with the switch member and into engagement with its contact.
5. A combined ignition and lighting switch, comprising an insulating base, a contact mounted thereon, a contact spring mounted on the base and adapted to be moved into engagement with the contact for controlling an ignition circuit, said contact spring being bent to form a loop, a guide on the base engaged by the sides of the loop for preventing lateral movement of the contact spring, a casing mounted on the base, a switch member rotatably mounted in the casing and having means engaged by the contact spring for locking the switch member against turning, contact arms carried by the switch member, contacts on the base engaged thereby for controlling a lighting circuit, a plunger mounted in the switch mem-
- ber and engaging the contact spring, and a key removably fitting in the switch member and engaging the plunger to force the contact spring out of locking engagement with the switch member and into engagement with its contact.
6. In a locking switch, a rotatably mounted switch member having spaced locking shoulders, a spring mounted in a fixed position and adapted to fit between the locking shoulders thereof to prevent the turning of the switch member, an electrical contact controlled by the movements of the spring contacts carried by the switch member, stationary contacts engaged thereby for controlling a circuit, and a key removably fitting in the switch member and adapted to force the spring out of engagement with the locking shoulders.
7. In a locking switch, a rotatably mounted switch member having a pair of spaced locking shoulders, a spring locking member fitting between the locking shoulders of the switch member to prevent the turning thereof, contacts carried by the switch member, stationary contacts engaged thereby for controlling an electrical circuit, a handle for turning the switch member provided with a keyhole slot and a cylindrical chamber communicating therewith, a cylindrical slotted key guide fitting in the cylindrical chamber of the handle and provided with a central projection, a tubular plunger fitting on the projection of the key guide and engaging the spring, and a removable key fitting in the keyhole and through the slot of the key guide and engaging the plunger to force it against the spring and move the spring out of locking engagement with the switch member.
8. A locking switch, comprising a movable locking member for controlling an electrical circuit, a switch member for controlling another electrical circuit engaged and locked by the locking member, and a key for moving the locking member.
9. A combined lighting and ignition switch, comprising an ignition circuit controlling member, a movable lighting circuit controlling member adapted to be locked against movement, and a key for unlocking the lighting circuit controlling member and when inserted adapted to move the ignition circuit controlling member to render the ignition circuit effective.
10. In a combination lighting and ignition switch, a normally locked movable lighting switch member, a key adapted to be inserted therein and an ignition circuit controlling switch member, the insertion of the key serving to unlock the lighting switch member and to move the ignition switch member to render the ignition circuit effective.
11. In a combination lighting and igni-

tion switch, a normally locked movable lighting switch member, an ignition switch member, and a key adapted to be inserted in the lock to unlock the lighting switch member and to move the ignition switch member to a position for rendering the ignition circuit operative.

12. In a combination lighting and ignition switch, an oscillating switch member for controlling a lighting circuit and having various positions for effecting different conditions in the lighting circuit, locking means for locking the lighting switch member in its various positions, a key fitting in said locking means, the insertion of the key serving to release the locking means, and an ignition switch operated by the insertion of the key.

13. In a combined lighting and ignition switch, a casing, a lighting switch member revolvably mounted therein, a stop limiting the movements thereof, means for holding the lighting switch member in various operative positions within its arc of movement for effecting different conditions in the lighting circuit, means for locking the lighting switch member in its various positions, a key adapted to be inserted in the locking means to release the locking means, and an ignition circuit controlling means dependent upon the presence of the key.

14. In a circuit controller, two switches with their operating means mounted one within the other, a single terminal head for both switches, and a removable key required for the operation of one of the switch operating means.

15. In a circuit closer, two switches having their operating means mounted concentrically one within the other, a single terminal head for both switches, and a centrally fitting removable key required for the operation of one of the switches.

16. In a circuit controller, two switches having their operating means arranged concentrically one within the other, a single terminal head bearing contacts for both switches, the inner switch operating means being normally inaccessible, and a removable handle by which said switch operating means may be operated.

17. In a circuit controller, two switches with their operating means arranged one within the other, a removable key fitting therein, one of the switches being incapable of operation when the key is removed, and a single terminal head having contacts for both switches.

18. In a circuit controller, two switches with their operating means arranged concentrically one within the other, a rigidly attached handle for the operating means of one switch and a removable key for the

operating means of the other switch, the circuit of the first switch being controlled by turning the rigidly attached handle and the circuit of the second switch being controlled by the attachment of the removable key, and a single terminal head bearing contacts for both switches.

19. A switch, a key-operated lock therefor, and a second switch operated by the key-actuated movements of the lock.

20. A switch, a lock therefor, a key for the lock, and a second switch having connection with the key for operation thereby.

21. In a circuit controller, a switch casing, a base forming a terminal head therefor, a switch member within the switch casing and engaging the contacts of the terminal head, a handle for the switch member projecting through the casing, and a second switch within the switch casing and cooperating with the contacts of the terminal head and having its operating handle fitting removably within the handle of the first mentioned switch.

22. In a circuit controller, a switch casing, a switch member within the switch casing, a handle for the switch member projecting through the front of the switch casing, a terminal head forming the back of the switch casing and having contacts engaged by the switch member, a second switch member within the casing engaging a contact of the terminal head, and a removable handle for the second switch member fitting concentrically within the other handle.

23. In a circuit controller, a casing, a switch member rotatably mounted therein, a handle for the switch member passing through the front of the casing, a terminal head forming a back for the casing and provided with contacts, spring actuated contacts on the switch member bearing on the terminal head and engaging contacts thereof, a second switch member within the casing also engaging a contact of the terminal head, and a handle for the second switch member removably mounted concentrically within the handle of the first switch member.

24. A lighting switch and an auxiliary switch for automobiles and the like, a removable actuating member for said auxiliary switch, and means controlled by said actuating member for rendering said lighting switch inoperative.

In testimony whereof, I affix my signature, in presence of two witnesses.

STEPHEN F. BRIGGS.
